UNITED STATES PATENT OFFICE

103,126

DESIGN FOR A SHOE

Theodore Samuels, St. Louis, Mo.

Application November 10, 1936, Serial No. 65,824

Term of patent 3½ years

To all whom it may concern:

Be it known that I, Theodore Samuels, a citizen of the United States of America, residing in St. Louis, county of St. Louis, and State of Missouri, have invented a new, original, and ornamental Design for a Shoe, of which the following is a specification, reference being had to the accompanying drawing, forming part thereof,

Figure 1 is a plan view of a shoe showing my new design.

Figure 2 is a side elevational view of a shoe as shown in Figure 1.

The essential features of my design reside in an open shank type of a shoe having the vamp portion thereof constructed of two elements, the one overlapping the other and having its upper portion divided so as to form two straps which join with the upper quarters on either side thereof.

I claim:

The ornamental design for a shoe substantially as shown and described.

THEODORE SAMUELS.
